(57) CLAIM

The ornamental design for a shuffleboard table, as shown and described.

DESCRIPTION

FIG. 1 is a perspective view of a shuffleboard table.

FIG. 2 is a right side view of the shuffleboard table of FIG. 1. The left side view is identical to the right side view.

FIG. 3 is a front view of the shuffleboard table of FIG. 1 showing our claimed design. The rear view is identical to the front view.

FIG. 4 is a top view of the shuffleboard table of FIG. 1; and, FIG. 5 is a bottom view of the shuffleboard table of FIG. 1. The features shown in broken lines are for illustrative purposes only and do not form part of the claimed design.
